UNITED STATES PATENT OFFICE

EDWARD WALPER, OF BROOKLYN, NEW YORK, ASSIGNOR TO WESTINGHOUSE ELECTRIC & MANUFACTURING COMPANY, A CORPORATION OF PENNSYLVANIA

SWITCH MECHANISM

Application filed May 28, 1928. Serial No. 380,712.

My invention relates to switch mechanism, and particularly to panel switches of the tumbler-action type, commonly used for controlling branch line house wiring circuits.

One object of my invention is to provide a tumbler-type switch of simple construction and which may be readily assembled.

Another object of my invention is to provide a tumbler-type switch wherein the operating handle positively initiates movement of the switch member toward open or closed positions prior to operation of the switch member by the over-center actuating spring.

A further object of my invention is to provide a single pole tumbler type switch of compact construction, and which may be assembled upon a fuse panel beside a similar single pole switch mounted on the panel without necessitating an increase in width 20 of the standard panel unit, thus enabling the production of a fuse and switch panel containing the control apparatus for two separate circuits.

These and other objects that will be made apparent throughout the further description of the invention are attained by means of the apparatus hereinafter described, and illustrated in the accompanying drawings, wherein,

Figure 1 is a top plan view of a fuse and switch panel embodying features of my invention.

Fig. 2 is a longitudinal section through a fragment of the panel taken on line II—II of Fig. 1, and showing a tumbler type switch unit in side elevation, and

Fig. 3 is a transverse section through the panel shown in Fig. 1, taken on the broken line III—III thereof and showing the tumbler switch units in end elevation.

Referring to the drawings, the panel unit comprises an insulating base 4 upon which is mounted a pair of separate fuse receptacles 5 and 6, that are connected through conductors 7, which are disposed on the rear surface of the panel, to contact terminals 8 having integral contact blades 9 extending normal to the front face of the panel. A similar pair of contact terminals 11 is provided 50 with contact blades 12 that are mounted ad-

jacent the end of the panel base 4 to which the load conductors (not shown) are connected.

A recess 13 is provided in the panel between the contact blades 9 and 12 and a pair of similar tumbler type switches 14 are mounted in the recess 13 and are provided with switch arms 15 for engaging and connecting the contact blades 9 and 12, as illustrated in the drawing.

Each switch unit is of the single pole type and comprises a frame member 16 of U-shape, having a bottom portion 17 and a pair of spaced parallel wing portions 18 that are provided with openings 19 and notches 21 that extend inwardly from the base portion as indicated in Fig. 2.

A switch carrier 23 of U-shape, provided with integral journals 24, is pivotally mounted upon the frame, the journals 24 being pivoted in bearing openings 25 in the side wings 18 of the frame. The switch arms 15 are secured to the carrier 23 upon lugs 25, the switch arm being clamped between metal washers 26 and insulated from the carrier by insulating washers 27. The lugs 25 are peened at their outer ends to fix the switch arms in assembled position upon the carrier.

The carrier is actuated by means of an insulating operating handle 28 that is pivoted for rotation upon the shaft 29 that connects the outer end of the frame wings 18. The operating handle is provided with an operating member 31 that is embedded in the handle and moves with it. The operating member 31 is provided with a notch 32 that engages a notch 33 in the outer end of a pintle 34 which is slidably mounted upon the cross bar 35 and the carrier 23, the free end of the pintle 34 being forked to receive the cross bar 35.

A spring 36 surrounding the pintle is confined between the enlarged outer end of the pintle and the cross bar 35 and serves to move the switch to either of its limited positions with a snap action when the spring has been moved past a center line connecting the shaft 29 and the cross bar 35 of the carrier. Movement of the carrier is limited by the sides 37 of the notches 21 and movement of the operat-

ing handle is limited by lugs 38 extending transversely from the operating member 31 and which engage the edges 39 of the openings 19.

5 It will be apparent from the foregoing that when the operating handle is turned in the clockwise direction as indicated in Fig. 2, the operating member 31 will first cause the pintle 34 to be moved inwardly and compress the spring 36. When the center of the spring 36 has been moved past the above-mentioned center line, the switch will be moved to the open position with a snap action. To close the switch, the operating handle is moved in 15 the reverse direction, causing the switch arm, through the medium of the carrier and the spring 36, to move to the open position.

The switch arms sometime become fastened to the contacts due to corrosion or 20 overheating thereof, and it is an object to provide means for initially moving the switch arm with respect to the contacts before the spring 36 has been moved over center, in order to permit it to move the switch 25 to open position with a snap action. The carrier 23 is provided with extensions 41 that are adapted to be engaged by the lugs 38 on the operating member 31. After the operating handle has moved a predetermined distance 30 one of the lugs 38 engages one of the extensions 41, and causes the carrier to be rotated before the spring 36 has been moved to its over-center position. By reason of this construction, the switch arm is positively 35 moved by the operating handle, after the latter has moved a predetermined distance. Because of the lost motion connection between the operating handle and the switch arm, the latter is free to move to either open 40 or closed position with a snap action in response to the movement of the spring 36, regardless of the position of the operating handle.

The construction is compact and by reversing the positions of two similar tumbler switches, the switch arms are disposed on the outer sides of the carriers in a position to engage the contact blades 9 and 12. Thus, two single pole switches may be connected 50 on the same panel in series with two separate fuse receptacles, thereby enabling the mounting of a control apparatus for two separate circuits upon one insulating base.

While I have illustrated but one embodiment of my invention, it will be apparent to those skilled in the art that various changes, modifications, substitutions, additions and omissions may be made in the apparatus illustrated without departing from the spirit 55 and scope of my invention, as set forth in the appended claims.

I claim as my invention:

1. A tumbler switch comprising a pair of spaced frame members having two pairs of 60 openings therein, a switch member of U-

shape, pivotally mounted upon the frame members and having a transverse portion on one side of the axis of rotation thereof, extending through one set of openings in the frame members for engaging the frame member and limiting movement of the switch member and having extensions on the other side of the said axis, an operating member pivoted between the frame members and having oppositely extending lugs entering the other pair of openings for limiting movement of the operating member and for engaging the said extensions for positively moving the switch member after the operating member has moved a predetermined distance 70 in either direction, and an over-center spring 75 for connecting the operating member and the switch member.

2. A tumbler switch comprising a support member, a switch member pivotally mounted thereon, and movable to different positions, an operating member for the switch member pivotally mounted upon the support member, an over-center spring connecting the operating member and the switch member for moving the switch member to the said positions with a snap action when the center of the spring has been moved past the center line of the pivots of the said members, and means on the said operating member for engaging the switch member and initiating movement of the latter after the operating member has moved a predetermined distance and before the spring has moved past the said center line and for engaging the said support for limiting movement of the operating member in either direction.

In testimony whereof, I have hereunto subscribed my name this 10 day of May, 1928.

EDWARD WALPER. 105
